Primary Examiner — Richard E Chilcot

(57) **CLAIM**

The ornamental design for agricultural robot, as shown and described.

DESCRIPTION

1. Agricultural robot

FIG. 1.1 is a front perspective view of an agricultural robot showing the new design;

FIG. 1.2 is a right side elevation view thereof;

FIG. 1.3 is a top perspective view thereof;

FIG. 1.4 is a rear perspective view thereof.
